FLUID DISPENSING DEVICE

Charles Mankouski, Portland, Oreg.

Application August 24, 1942, Serial No. 455,864

1 Claim. (Cl. 222—340)

This invention relates generally to the dispensing of a fluid such as lotions, liquid soaps, hair oils, etc., and particularly to a fluid dispensing device.

The main object of this invention is to construct a fluid dispenser which is easily attachable to a container from which the fluid may be forcibly ejected in measured quantities without wasting the fluid or being untidy or unsanitary.

The second object is to construct a device in a manner consistent with modern methods of producing objects from plastic materials and also in a manner to reduce to a minimum the weight of the parts required to avoid the excessive use of the plastic material.

The third object is to construct a device of the class described wherein a positive ejection valve is employed to insure the delivery of a predetermined quantity of liquid regardless of the speed or the manner in which it is operated.

The fourth object is to provide a modified form of ejection thereby for use in connection with materials having different degrees of viscosity.

I accomplish these and other objects in the manner set forth in the following specification as illustrated in the accompanying drawing, in which:

Fig. 1 is a side elevation of my device showing same in place on a bottle.

Fig. 2 is a plan of Fig. 1.

Fig. 3 is a vertical section of the device taken along the line 3—3 in Fig. 2.

Fig. 4 is a section taken along the line 4—4 in Fig. 3.

Fig. 5 is a bottom view of Fig. 3.

Fig. 6 is a view similar to Fig. 3 but showing the operating button depressed.

Fig. 7 is a plan of a modified form of the device, not especially adapted for light or fast flowing fluids such as liquid soaps, hair oils, etc., but intended for thick fluids, creams and hand lotions.

Fig. 8 is a fragmentary section taken along the line 8—8 in Fig. 7.

Similar numerals refer to similar parts throughout the several views.

Referring in detail to the drawing, there is shown the common form of bottle 10 having a threaded neck (not shown). On the neck of the bottle 10 is screwed the internally threaded neck 11 of my device which is provided with a somewhat flaring base 12 having the hollow portion 13 for lightening purposes. The threads 14 may be of any convenient type.

A dividing wall 15 is provided with a central

opening 16 which is in alignment with the opening in the neck of the bottle 10.

The wall 17 forms one end of the device above the dividing wall 15 while the rounded wall 18 forms a second end wall for the space above the member 15. The sides 19 are tangent to the members 17 and 18. A cover 20 is provided with a friction rim 21 and placed over the compartment 22 formed within the members 16, 17 and 18. The cover 20 has a cylindrical recess 23 formed at the bottom thereof which terminates in the uppermost cylindrical portion 24 of somewhat less diameter than is the portion 23.

Guide ribs 25 are placed within the portion 23 whose interior edges 26 are in alignment with the cylindrical portion 24. The cap 27 forms a closure for the upper end of the cylindrical portion 24 and is provided with a very small outlet opening 28 whose outer end terminates in an outwardly projecting tip 29 and whose inner end 30 extends into the hub 31. The disc 32 forms a piston within the opening 24 which is capable of being guided by the ribs 25.

In the top side of the member 20 is formed a cylindrical cavity 33 in the center of which is formed a tubular wall 34 which is supported in the cavity 33 by the bottom 35. Within the tubular wall 34 is disposed a piston 36 provided with a sealing ring 37. The piston 36 is formed on the piston rod 38 which also guides within the tubular wall 34. The lower end 39 of the rod 38 is U shaped and its upright portion 40 is integral with the hub 31.

On the upper end of the rod 38 is formed a cylindrical head 41 which is pressed into the cap 42 of the hollow push button 43. The push button 43 can move freely within the cylindrical cavity 33. A spring 44 of suitable compression strength is interposed between the push button 43 and the bottom 35, encircling the tubular wall 34.

It will be seen that the pressure of the finger 45 upon the button 43 will move the button 43 to the position shown in Fig. 6, causing the piston member 32 to move downwardly as shown in Fig. 6 and permit fluid to flow between the ribs 25 into the space 24 when the bottle 10 is inverted or turned on its side. As the button 43 is released, the liquid is trapped in the cylindrical portion 24, the instant the disc 32 passes the shoulder 46 causing material to be ejected from the opening 28.

In the form of the device shown in Figs. 7 and 8, there is a slight modification in which the tip 29 and the inner end 30 are omitted and the

small opening 47 extends through the cap 48, the disc 32 being the same as in the first described form of the device.

This form of the device is especially adapted for the heavier or more viscous fluids such as lotion, etc.

It will be seen that throughout this device there is a consistent effort made to design the parts to make them adaptable from plastic materials, and also that the completed articles function in a manner particularly desirable for users of lotions, liquid soaps, hair oil, etc. That is, the operating pressure is stored up in the spring 44 by means of the finger 45, so that the release of the finger will bring about the ejection of the materials. Moreover, there is no opportunity for a playful or mischievous person to use this device as a gun or spray, as it is incapable of exerting a greater force than is stored up within the spring 44 itself.

While plastics would, in most cases be preferable, it is obvious that in many instances die casting could be employed to advantage.

While I am aware that numerous forms of fluid dispensing devices have been invented in the past, I do not intend to cover all such devices broadly,

but I do intend to cover all such forms and modifications as fall fairly within the appended claim.

I claim:

The fluid dispensing device consisting of a threaded bottle cap having a chambered recess formed between the threaded portion thereof and the closure therefor, said closure having an inwardly opening cylinder formed therein, said cylinder having a piston normally occupying same, said cylinder having extension guides for supporting said piston when withdrawn from said cylinder, said closure having an opening therein through which fluids may be ejected by said piston, said closure also having an outwardly opening cylindrical cavity formed therein within which is a tubular wall communicating between the interior of said chambered recess and the atmosphere, a piston within said tubular wall, a U shaped piston rod connecting the two pistons and extending outwardly from said tubular member, a hollow push button within said outturned cylindrical cavity having a spring therein surrounding said tubular member, said push button being secured on the outer end of said projecting piston rod.

CHARLES MANKOUSKI.
